DESIGN FOR A CHILD'S SEAT OR SIMILAR ARTICLE

Carl H. Hasche, Glendale, Calif.

Application January 19, 1946, Serial No. 125,754

Term of patent 14 years

(Cl. D34—15)

To all whom it may concern:

Be it known that I, Carl H. Hasche, a citizen of the United States and a resident of the city of Glendale and State of California, have invented a new, original, and ornamental Design for a Child's Seat or Similar Article, of which the following is a specification, reference being had to the accompanying drawing, forming part thereof, in which:

Fig. 2 is a side elevation thereof, and

Fig. 3 is an elevation as seen from the left of Fig. 2.

I claim:

The ornamental design for a child's seat or similar article, substantially as shown,

CARL H. HASCHE.
